Des. 236,292
Patented Aug. 19, 1975

236,292

CRACKER

Albert C. Friedrich, San Jose, Calif., assignor to
Wine Barrel Corporation, Campbell, Calif.

Filed Nov. 8, 1973, Ser. No. 414,074

Term of patent 14 years

Int. Cl. D1—01

U.S. Cl. D1—15

FIG. 1

FIG. 2

FIG. 3

FIG. 1 is a front elevational view of a cracker showing my new design, the rear view being identical thereto;

FIG. 2 is a side view of the cracker; and

FIG. 3 is a bottom view of the cracker.

I claim:

The ornamental design for a cracker, as shown and described.
